UNITED STATES PATENT OFFICE.

ELIAS H. KELLEY, OF NEW YORK, N. Y.

CHECK-EXHIBITING DEVICE FOR VENDING-MACHINES.

1,204,453.

Specification of Letters Patent.

Patented Nov. 14, 1916.

Original application filed December 17, 1909, Serial No. 533,638. Divided and this application filed October 27, 1910. Serial No. 589,302.

To all whom it may concern:

Be it known that I, ELIAS H. KELLEY, a citizen of the United States, residing in the borough of Manhattan, city, county, and 5 State of New York, have invented a new and useful Improvement in Check-Exhibiting Devices for Vending-Machines, of which the following is a description.

This invention relates to check exhibiting 10 devices for vending machines and has particular reference to mechanism or means by which coins or checks deposited in a coin-controlled apparatus may be displayed or exhibited, for a definite period of time during 15 the operation of the machine, in order that the character of said coins or checks may be ascertained or discovered prior to being deposited in the receptacle or coin-box of the apparatus.

20 My invention has especial reference to apparatus of the nature disclosed in my application Serial No. 533,638, filed December 17, 1909, of which this application is a division; but, I desire it distinctly understood that 25 my present invention is not limited in its application and use to apparatus of the particular type illustrated in my said parent application. Therefore, certain of my claims will not be limited to any particular 30 type of apparatus, but will cover broadly exhibiting devices having in mind the functions to be obtained.

Among the objects of my invention may be noted the following: to provide an electrically-driven vending machine with illuminating means for exposing certain parts of the machine to public view; to provide means, in a coin-controlled apparatus, for receiving the device, deposited in the machine for a functional delivery, and at the same time exposing the same for inspection; to provide a check-exhibiting device for vending machines which will expose the check to view for a definite period; and to 45 provide simple and effective means for securing the foregoing objects which are capable of application to practically any given type of machine.

With the above objects in view, and others 50 which will be detailed during the course of this description, my invention consists in the parts, features, elements, combinations of elements and mechanisms all as hereinafter described and claimed.

55 In order that my invention may be

clearly understood, I have provided drawings wherein:

Figure 1 is a plan view of two of the slide mechanisms of my machine, the said view also showing certain features of the coin-detecting mechanism, and fraud-preventer or coin-gage, merely to show the relation and arrangement of my invention in a given coin-controlled apparatus; Fig. 2 is a vertical section on a line extending from front 60 to rear of the machine and substantially centrally thereof, showing only the lower portion of the machine and being intended to disclose only the arrangement of the display-device, the chute, conveyer and coin-box; and Fig. 3 is a diagrammatic view of the electric circuits of the entire machine, to illustrate how the same is electrically operated and the manner in which the display-lights are kept lighted at all times whether 70 the machine be in operation or not; Fig. 4 is a vertical, sectional view through a portion of the apparatus taken substantially centrally of one of the slides and adjacent mechanism, in this instance the view being 75 taken through the 10¢ slide or lower one which is shown in Fig. 1 of the drawings.

Referring to the drawings, the numeral 1, Fig. 2, indicates the base of the frame of the machine, 2 the rear wall and 3 the 80 front wall of the lower extension in which the coin-box 4 is located and in which the conveyer and display-device are also located. The front wall 3 is provided with the door 5 hinged to the base at 6 and provided with 85 any suitable means for locking the same after the coin-box has been inserted therein. The support 7 carries the slide-plate 8, in which the coin-slides 9 reciprocate, and said support has set therein a piece of transparent material 10, the edges of which are beveled to coöperate with the correspondingly-formed edges of the opening of the support. A suitable frame 11 for the transparent material 10 is arranged in any effective way to hold the said material in the support, as clearly shown in Figs. 1 and 2, the same being made, however, of detachable strips or bars secured to the bottom of the support. In Fig. 1, several coin-slides 9 are shown, as well as transparencies 10, and the arrangement of the latter in the machine is particularly shown in Fig. 1, wherein it will be seen that, in the given example of the application of the display- 110

device, the transparent portion 10 is arranged directly over the coin-conveyer, generally indicated by 12, and that in this particular instance the chutes 13 and 13^a, 5 coöperating with adjacent coin-slides, extend into coöperation with said conveyer. The transparency may consist of glass, mica, or any other suitable material held in the groove of the support, as above indicated. 10 The coin-conveyer consists of the endless chain, generally indicated by 12, as aforesaid, driven by sprocket-wheels 14, the rear one of which is carried by a shaft 15, bearing in standard 15^a, and the front one of 15 which is carried by a shaft 16, bearing in standard 16^a, said shaft being driven by the gear 17, which meshes with the pinion 18, carried on the counter-shaft 19 also journaled in a standard 16^a, secured to the base 20 of the machine. The shaft 19 also carries a sprocket-wheel 21, driven by the chain 22, in turn driven by the sprocket-wheel 23, carried by the main shaft 24 of the machine, which may be actuated in any suitable manner, but which in this instance is driven by chain and sprocket 25, actuated by a power shaft 26, shown in Fig. 3. The conveyer chain 12 is provided with a series of cups 27, each of which is, in this instance of my 25 invention, formed into a large compartment 28 and a small compartment 29, the object of which is to receive from the respective chutes 13 and 13^a the large and small coins which are dumped thereinto from the coin-slides 9 of the machine. It is immaterial what speed the conveyer is given in its travel under the chutes, but it is the object of my invention to make such speed slow so as to enable the coins in the cups of the 30 conveyer to remain in sight through the transparency 10, during several coin-controlled operations of the machine, which, obviously, will be intermittent and dependent upon the coins or checks placed in the 35 coin-slides. The coin-cups 27 are so connected to the chain 12 that several will be in alinement on the top of the chain directly under the transparency at any given period in the travel of the chain and, when a cup 40 reaches the end of its travel, it will be turned completely over so as to dump or drop a coin therein directly into the opening 30 of the coin-box 4, into which the coin is directed by a back-plate 31, a guard-plate 50 32 and the open lid 33 of the cover 34 of the coin-box, it being understood that said lid 33 is normally held open, as shown in Fig. 2, at all times during the operation 55 of the machine, or when said coin-box is 60 in proper position in the machine. Further details of this construction are not herein set forth since such details form no part of my present invention, but are set forth in my parent application.

65 Directly under the transparency 10, I

have located, according to my invention, an incandescent electric-lamp 35, the base 36 of which is suitably secured to a bracket or lug 37, carried in any suitable manner on the bottom of the support 7, directly in rear of the opening in which the transparency 10 is set, so as to hold the lamp in position under one end of the transparency and directly above the cups of the coin-conveyer. 70

Other parts of the machine in connection 75 with which I have chosen to illustrate my invention, are the coin-slide lock, the parts of which are generally indicated by 38, a coin-gage and slide-lock, parts of which are generally indicated by 39, the coin-testing mechanism, parts of which are generally indicated by 40, and the tripping mechanism, parts of which are generally indicated by 41.

The electric lights used for illuminating 80 purposes, in accordance with my invention, are connected in the electric circuit of the machine in accordance with the diagram shown in Fig. 3. Assuming a source of power 42, the current will traverse the lead *a* to that one of the brushes 43 which co-operates with the slip-ring 44, near the magnetic clutch-member 45, and passing through the latter will, by the proper lead, go to the slip-ring 46, and its coöperating brush 47 nearer to the motor 48, through 85 which it passes and, still following the lead *a*, will run to the first one of the contact-members 49, with which the switch-bar 50 coöperates, this contact-member being suitably insulated and supported in the machine. At this point, the current cannot 90 pass, in the normal condition of the machine, and can only pass when the contact-member 51 is in coöperative relation to the spring-contacts 49 to close the circuit. 100 Hence, the current will pass by way of the lead *b* to, for example, the twenty-five cent slide on the extreme right of the machine, and will run to the outer one of the contact-members 52, which, if the contact-device 53 105 be in coöperative relation, with said spring-contacts 52, will pass the current by way of the lead *b* through to the source of power, as indicated by the negative sign. This completes a circuit including the magnetic 110 clutch, the motor and the twenty-five cent slide of the machine, and thereby drives the shaft 26, and transmits its motion through the sprocket-chain 25 to the driving-shaft 24, and, in accordance with the rule of 115 action of the machine, will impart movement resulting in a functional operation of the machine. The functional operation of the machine includes the actuation of the sprocket 21 by chain 22, the pinion 18, the gear 17, and the actuation of the conveyer by sprockets 14 and chain 12, thus causing 120 the coin-cups to travel during the prescribed period of time and the predetermined distance under the electric light, thus enabling 125

130

an operator or the public to see the contents of the coin-cups at the top of the conveyer through the transparency 10, in the light of the lamp 35. At the end of a given operation, the circuit in the lead *b* is broken, this taking place just after the circuit *a* is closed between the contact-members 49 and 51, resulting in shunting the current along circuit *a*, the current being thus continued along the latter to the return-lead *b* and to the negative side of the main or generator. By causing the opening of the circuit at 52 to take place just after the closing of the circuit at 49, sparking is eliminated and the 15 operation of the machine is rendered continuous. Then the switch-bar 50 is automatically moved back, thus withdrawing its contact 51 from the contacts 49, thus breaking circuit *a*, the torque of the clutch 45, the 20 motor-circuit, and stopping the machine, this action taking place at the end of a complete rotation of the driving-shaft 24.

Assuming that the ten-cent slide is to be operated, when said slide is forced in and 25 all the conditions are right, the contact-member 54 of said ten-cent slide mechanism will drop into coöperative relation with the spring-contact 55, thus completing the circuit through the lead *a* to the clutch 45, and thence, as before described, through the 30 motor 48 and the lead *a* to one of the spring-contacts 49, and through the lead *b*, to the lead *c*, to the said spring-contacts 55 of the ten-cent slide mechanism. The circuit 35 being completed by the contact-member 55, the current will continue through the lead *c*, to the lead *b*, and thence through to the negative side of the main or generator in the same manner as before described with reference 40 to the twenty-five cent slide. The main shaft will be actuated, as before described, and at the proper time during its operation the contact-member 51 will be driven into coöperation with the spring-contact 49, and thus complete the circuit through the lead *a* and thence through the lead *b*, to the negative 45 side of the main or generator, as previously described, the circuit *c* being opened as described with reference to circuit *a*. Assuming that the nickel-slide is to be operated, the same action will take place with regard to operating the slide and tripping the contact 56 into action, thus completing the circuit through the lead *a*, the magnetic 50 clutch 45, the motor 48, the lead *a*, the lead *b*, the lead *c*, and thence to lead *d*, since the circuit is open in the lead *c*, also in the lead *b*, and thence through the spring-contacts 55, the contact-member 56 being in coöperation 55 with the latter, and thence continuing through the lead *d* to the lead *b*, and to the negative side of the generator or main, as previously described, the operation of the driving-shaft, coöperation of the contact-member 49 and 51, and the breaking of the

circuit at 56—57, in the lead *d*, being as previously described with reference to the ten and twenty-five cent slides.

As has been previously suggested, the electric-lights 35 are operated to illuminate 70 the coin-cups of the conveyer coöperating with the chutes of the several coin-slide mechanisms for the purpose of enabling inspection of the coins deposited in said cups. This is accomplished by tapping the lead *a* 75 between the source of current and the magnetic clutch and carrying the current through lead *e*, and through the several lamps 35, arranged in parallel, to the negative lead *b*. Hence, it will be seen that the 80 lamps 35 are in an independent circuit and will be constantly lighted to illuminate the conveyer and the coin-cups.

Referring particularly to Fig. 4, it will be seen that the coin slide 9 is provided with 85 an aperture 58 in which the coin is placed, and which, when said coin successfully passes the testing devices 59 and 39, will reach the aperture 60 in the throat-plate 61, which, as shown in Fig. 1, extends transversely of the coin-slides 9 and through which, upon the movement of the throat-plate 61, the coin may be dropped through the aperture 62, in the plate, into the chute 13, from which it slides into one or the 90 other of the conveyer cups 27. The coin slide is manipulated by the knob 63 and is returned to normal position by the spring 64, one end of which bears against the collar 65, and the opposite end of which bears 95 against the frame of the machine or a bracket thereof as at 66. When any one of the slides has been successfully forced to its innermost position, the lower rod 38, Figs. 2 and 4, enters between the balls of 100 the carrier at the free end of the rod and prevents the other slides from operating the machine. When the coin reaches the throat-plate 61 and is centered over the apertures 60 and 62, the plunger of the testing mechanism 40 will have been tripped into 105 action by the displacement of the tripping mechanism 41, thus bringing about the co-operation of the contact members 54 and 55, as previously described, the member 54 dropping under impulse of gravity and spring 67, as will be readily understood. When the coin-slide 9 has been thus forced to its extreme inner position, it cannot be returned until the proper time by reason of the co-operation therewith of the locking dog 68, which drops into a notch 68a in the end of 110 said slide, and is thus maintained under stress of the spring 69, secured to a suitable fixture of the machine at the lower end, and to the pin 70 extending laterally from the arm 71, fixed to the shaft 72 relatively to the dog 68, which is also fixed to said shaft. During the operation of the machine and the 115 single revolution of the main shaft 24, the 120

125

130

21
 arm 71 is lifted by the cam 73 against the stress of the spring 69, thus lifting the dog 68 and releasing the coin slide 9, and thus permitting the spring 64 to return the same to the normal position shown in Fig. 4. At the same time, the segmental gear 74, fixed to the shaft 24, will engage the rack-bar 75 of the tripping mechanism 41, which rack-bar, when said mechanism has been tripped, will move forward into the plane of action of said segmental gear 74 for co-operation with the latter, this being brought about by the unseating of the pin 76 carried by said rack-bar from the rest 77 in the frame member 66 of the machine. The tripping of the mechanism just described by unseating the rod thereof from the rest or support at 78 permits the bifurcated arm 79, affording a support for the lug or bracket 80, to drop, thus removing the support for the lever of the testing mechanism 40 and permitting the co-operation of the contacts 54 and 55, as previously described.

The complete circuit through the machine and the mode of making and breaking the various branch circuits have been shown and described because of the co-operation and functional relation of the same to the subject-matter of my present invention; and it will be understood that one of the important features of my invention resides in the fact that the lamps are constantly lighted and the conveyer is intermittently actuated to move a predetermined distance under control of the various coin-slides and at the end of a given operation of the machine, under such control, the conveyer comes to rest, thus exposing the coins in the cups directly to view under the light of the lamp. Thus, the coin in a given cup will be exposed to view through several functional operations of the machine according to the timing of the operating mechanism.

Having thus described my invention, what I claim and desire to secure by Letters Patent is:

1. A vending machine having, in combination, a horizontal cover-plate; means by which a coin may be passed through said plate; a conveyer located and traveling directly beneath said plate in position to receive said coin; means for actuating said conveyer; a transparency in said plate above said conveyer; and means for illuminating the conveyer so that observation can be made thereof through the transparency.

2. A vending machine having, in combination, a coin conveyer, a reciprocable coin-slide and connections for controlling the operation of said conveyer, a chute communicating with said slide and conveyer, and lighting means arranged adjacent the conveyer so as to illuminate the latter.

3. In combination, a coin-conveyer, an electric circuit, a coin-slide, a chute between

the conveyer and slide, and means by which to cause the current in the circuit to drive the conveyer upon actuating the slide.

4. In combination, a coin-conveyer; an electric circuit; means for actuating the conveyer including means for opening and closing said circuit, and thereby intermittently actuating said conveyer; and an electric lamp for illuminating said conveyer, connected in said circuit so as to be kept constantly burning regardless of the opening and closing of the circuit.

5. A vending machine having a plurality of coin-receiving slides; a plurality of chutes co-operating with said slides and directed so as to deliver the coins at substantially a common point; a conveyer comprising a plurality of sets of coin-receptacles arranged to travel in co-operative relation to said chutes, one set of receptacles for each chute; and means for actuating said conveyer.

6. A vending machine having a coin-slide; a coin-conveyer; a chute communicating with the slide and conveyer; an electric circuit; means actuated by the coin slide for making and breaking the circuit and for actuating the conveyer; and a lamp connected in the circuit and arranged relatively to the conveyer to illuminate the same.

7. In combination, a reciprocatory coin-slide; a revolving coin-conveyer; a stationary chute co-operating with said slide and conveyer; a transparency arranged directly above the conveyer and at one side of the slide; and means for illuminating the conveyer arranged between the latter and the transparency.

8. In combination, a reciprocatory coin-slide; a movable coin-conveyer; a stationary chute co-operating with the slide and conveyer; an electric circuit; means actuated by the coin-slide for making and breaking the circuit and for intermittently actuating the conveyer; and a lamp connected in the circuit so as to be kept constantly lighted, said lamp being arranged relatively to the conveyer to illuminate the same.

9. A vending machine having, in combination, means for conveying a coin; means for receiving a coin and carrying it into the machine; and intermediate operating connections between the coin-receiving and the conveying means, whereby the coin may be carried into exposed position, after it has performed its functions.

10. A vending machine having, in combination, means for conveying a coin; means for receiving a coin and carrying it into the machine; intermediate operating connections between the coin-receiving and the conveying means; and means for receiving the coin from the conveyer after it has performed its functions.

11. A vending machine having, in combination, means for conveying a coin; means

for receiving a coin; intermediate operating connections between the coin-receiving and the conveying means; and means for receiving the coin after it has performed its functions, the conveyer including an endless chain of receptacles.

12. A vending machine having, in combination, means for conveying a coin; means for receiving a coin; intermediate operating connections between the coin-receiving and the conveying means; and means for receiving the coin after it has performed its functions, the conveyer including an endless device having coin-receiving means maintained at all times in fixed relation to said conveyer.

13. A vending machine having, in combination, means for conveying a coin; means for receiving a coin and carrying it into the machine; intermediate operating connections between the coin-receiving and the conveying means; means for receiving the coin after it has performed its functions, the conveyer including a rotary device, and means for intermittently actuating said conveyer from said connections to carry the coins to a point of observation.

14. A vending machine having, in combination, means for conveying a coin; actu-

ating means for said conveyer; coin-controlled means for starting the actuating mechanism into action; means whereby, according to the character of the coin, the actuating mechanism may or may not be started; and the means for operating the conveyer being in combination so that it will be operated irrespective of whether the actuating mechanism be started or not.

15. A vending machine having, in combination, coin delivery means including a plurality of conveyers; a plurality of coin-receiving devices; operating mechanism connecting said devices with the delivery means whereby any one of said devices may actuate the operating mechanism; means common to the said devices for supporting a coin placed in any one thereof; and means whereby said coin-supporting means may be operated to deposit a coin upon the conveyer complementary to the device operated.

In testimony whereof I have hereunto signed my name in the presence of two subscribing witnesses.
